(57) **CLAIM**

The ornamental design for a capsule for dental materials, as shown and described.

DESCRIPTION

FIG. 1 is a perspective view of a capsule for dental materials showing my new design;

FIG. 2 is a side elevational view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a perspective of a capsule for dental materials of the second embodiment showing my new design;

FIG. 8 is a side elevational view thereof;

FIG. 9 is a top plan view thereof;

FIG. 10 is a bottom plan view thereof;

FIG. 11 is a front elevational view thereof; and,

FIG. 12 is a rear elevational view thereof.

The broken lines showing portions of a capsule for dental materials represent non-claimed subject matter and forms no part of the claimed design.
